UNITED STATES PATENT OFFICE.

GEORGE R. BENNETT, OF GLEN OSBORNE, PENNSYLVANIA, ASSIGNOR TO ALBERT M. HANAUER, OF PITTSBURGH, PENNSYLVANIA.

LOADING-MACHINE.

1,383,594.

Specification of Letters Patent. Patented July 5, 1921.

Application filed February 5, 1917, Serial No. 146,706. Renewed March 5, 1921. Serial No. 448,746.

To all whom it may concern:

Be it known that I, GEORGE R. BENNETT, residing at Glen Osborne, in the county of Allegheny and State of Pennsylvania, a citizen of the United States, have invented or discovered certain new and useful Improvements in Loading-Machines, of which improvement the following is a specification.

The invention described herein, relates to mechanism for transferring material, such as coal, sand, etc., from the place where it has been deposited in mining or other operations, to cars whereby it may be removed. In general terms, the invention 15 consists of a trough provided at its front end with shovel-like members or fingers, which are adapted to be forced under the material to be removed, in combination with means for shifting the material as it is forced back from the fingers, along the trough, and means for directing the material into cars. The invention is hereinafter more fully described and claimed.

In the accompanying drawing, forming 25 a part of this specification, Figure 1 is a side elevation of my improved loading mechanism, Fig. 2 is a top plan view of the same, a portion of the traveling apron being broken away, and Fig. 3 is a sectional de- 30 tail view of the mechanism directly employed in moving the loading mechanism to and from position of operation.

In the practice of the invention, the parts or elements hereinafter described, are sup- 35 ported on a rigid metal frame 1, which in turn is provided with wheels 2 adapted to move along the surface on which the material is deposited, or along suitable rails. In mining operations, it would be generally 40 preferable to mount the loading mechanism on rails between which is arranged a rack 4 adapted to be engaged by toothed wheels, carried on the machine, and operated as hereinafter described for shifting the ma- 45 chine.

On the front portion of the frame, a trough 5 is arranged in an inclined position, said trough being provided at its front end with a pivotally mounted section 6, such section 50 consisting of, or being provided with, a series of shovel-like fingers 7. In the forward movement of the loading mechanism, as hereinafter described, these fingers are forced in under the material lying on the 55 ground or floor of the tunnel and to facili-

tate the pushing of the fingers under the material, it is preferable that a slight up and down movement be imparted to the fingers, so that they may loosen the material and work their way under the same. This movement can be effected in many ways, such for example, by cams 8 mounted on a shaft 9 which is so arranged that on the rotation of the shaft, the fingers will be raised by the cams and allowed to drop. The shaft 9 carrying the cams, is driven by an extension 10 on one of the worm conveyers hereinafter described, as clearly seen by reference to Figs. 1 and 2.

In order to move the material along the trough as the fingers and front end of the trough are moved under the same, suitable means, such as worm-conveyers 11 are employed. In the construction shown, the bottom of the trough is slotted and the shaft 70 of a series of worm conveyers 11 are so mounted on the under side of the trough that portions of the conveyers will project a short distance above the bottom of the trough. These conveyers are driven by the shaft 14 through beveled gearing as clearly shown in Fig. 2. The material is caused to move along the trough by the conveyers onto a traveling apron 15, which may be of any suitable form or type. In the construction 75 shown, these conveyers consist of belts passing around pulleys 16 and 17, arranged respectively upon the shafts 18 and 19. The shaft 18 is mounted in bearings 20 below the rear portion of the trough, so that the material passing from the latter will be received by the apron. The pulleys 17 are secured on a shaft 19, which has its ends mounted in adjustable bearings 23, which can be shifted by screws 21 so as to maintain the conveyer 80 under suitable tension. A chute 24 is arranged on the rear end of the machine and in such relation to the traveling conveyers, that the material will pass from the latter into the chute, and be directed into the cars 85 shown, these conveyers consist of belts passing around pulleys 16 and 17, arranged respectively upon the shafts 18 and 19. The shaft 18 is mounted in bearings 20 below the rear portion of the trough, so that the material passing from the latter will be received by the apron. The pulleys 17 are secured on a shaft 19, which has its ends mounted in adjustable bearings 23, which can be shifted by screws 21 so as to maintain the conveyer 90 under suitable tension. A chute 24 is arranged on the rear end of the machine and in such relation to the traveling conveyers, that the material will pass from the latter into the chute, and be directed into the cars 95 arranged in the rear of the loading mechanism.

The operation of the several parts herein described, can be effected by any suitable means or form of motor, but preferably by 100 electric motor 26. A pinion 27 on the shaft of the motor, intermeshes with the driving wheel 28, on which are also secured crank arms 29, the pin connecting such crank arms being adapted to oscillate a lever 30. This 110

lever is provided with a pivotally mounted pawl 31, adapted to engage the teeth on the ratchet wheel 32. The shaft of this ratchet-wheel has secured thereon a pinion 33 intermeshing with the gear wheel 34, on a shaft to which is also secured a gear-wheel 35, adapted to intermesh with the rack 4, and a pinion 36 intermeshing with a second pinion 37, also intermeshing with the rack. By the oscillation of the lever 31, the shaft carrying the gear-wheel 35, will be so rotated as to move the machine backward or away from the material to be loaded, but as the driving pinion 37 is driven from the shaft carrying the gear-wheel 35 through a pinion, the rotation of the pinion 37 will move the frame forward so as to force material up onto the trough 5. By the construction herein described, the machine can be moved slowly forward step by step, and shifted backward away from the loading position at a more rapid rate. The gear-wheel 35 and pinion 36 are loosely mounted upon their shaft, but are adapted to be operatively connected to the shaft by clutch mechanisms 41 and 42, which are moved simultaneously by the rods 43, one of the clutch mechanisms

being moved into operative position and the other into inoperative position.

I claim herein as my invention:

1. In a loading machine the combination of a trough consisting of pivotally connected sections, the front section consisting of a plurality of independent fingers, means for forcing the front section under the material to be loaded, means for vibrating the fingers forming the front section and means arranged in the trough adapted to pass under the material lifted by the fingers and shift the same to the rear of the machine.

2. In a loading machine the combination of a trough, a plurality of independent fingers connected to the front end of the trough, means for moving the trough to force the fingers under the material to be loaded, means for vibrating the fingers and means arranged in the trough for moving the material as it is forced onto the fingers to the rear of the machine.

In testimony whereof, I have hereunto set my hand.

GEORGE R. BENNETT.
